CONTROLLING MECHANISM FOR SAND TRAPS

Frank E. Saari, Chicago, and Grant V. W. Roth,
Evanston, Ill.

Application June 26, 1946, Serial No. 679,449

5 Claims. (Cl. 291—12)

1

The invention relates to track sanders for locomotives, and more particularly to the engineer's valve for controlling the delivery of the sand by compressed air, from the usual sand traps.

Heretofore, it has been common practice to employ valve-mechanism which includes a rotatable disk or element which is provided with a through-port and adapted to be set into positions for controlling respectively, the delivery of sand to the trap for clean-out blasts, and the discharge of sand for delivering it to the rails. In this mechanism, one face of the rotatable disk fitted against a seat in the casing which was provided with conduits communicatively connected to the sand traps respectively. In practice, it has been found that leakage is sometimes caused by imperfectly fitting casing sections or engaging faces of the disk and its seat, or particles becoming lodged between said faces, or from other causes, so that when the disk was set to cut off the supply of compressed air to the sand trap, a considerable volume of compressed air was wasted.

The main object of the invention is to provide valve-mechanism of this type which include an auxiliary self-closing valve, controlled by the rotative movements of the valve-disk, for automatically cutting off the supply of compressed air to the valve-disk chamber in the casing, and thereby practically eliminating unilateral pressure and reducing drag on the valve-disk for ease of its operation, and also preventing leakage of air from the casing while the valve-disk is set to cut off the delivery of air to the trap, in the event that the casing sections, or the engaging faces of the valve-disk and its seat in the casing, are imperfectly or defectively fitted, or particles become lodged between said faces.

Another object of the invention is to provide a valve of this type which is simple in construction and can be economically produced.

Other objects of the invention will appear from the detailed description.

The invention consists of the several novel features hereinafter set forth and more particularly defined by claims at the conclusion hereof.

In the drawings:

Figure 1 is a side elevation of a valve embodying the invention.

Figure 2 is a section taken on line 2—2 of Figure 1.

Figure 3 is a perspective of the rotatable valve-disk.

Figure 4 is a section taken on line 4—4 of Figure 2.

2

Figure 5 is a section taken on line 5—5.

Figure 6 is a section illustrating the auxiliary valve in its open position, to admit the passage of compressed air to the disk valve.

The invention is exemplified in valve-mechanism which comprises a casing formed of outlet and inlet sections 10 and 11, which are secured together by screws 12. A pipe 13 leading from a source of compressed air supply, is connected 10 to the section 11 of the casing. Pipes 14 and 15 are connected to receive air from separate conduits in the casing-section 10, and are connected respectively to the ducts in a pair of sand traps, for delivering clean-out blasts to the sand traps, as well understood in the art. Pipes 16 and 17 are connected to receive air from separate conduits in casing-section 10, and are connected respectively to deliver air for discharging sand from a pair of traps, as well understood in the art. A chamber 18, in the casing, is adapted to receive air from supply pipe 13, under control of the auxiliary valve hereinafter described. A valve-disk 19 is rotatable in the chamber 18, and has one of its faces fitting against the face 20 in casing section 10, which forms a seat for said disk. Disk 19 is rotatable by a stud 21, which is connected to the disk by a rib 22. Stud 21 has affixed thereto, a hand lever 23, which is provided with a spring pressed dog 24, adapted to engage a series of notches 26, formed in a segment on the casing-section 10, for yieldably holding the lever in its different selective and predetermined positions. A port 27 extends through valve-disk 19, and controls the flow of air from chamber 18, to a pair of ducts 28, 29, in casing-section 10, which are communicatively connected to pipes 14 and 15 respectively, and to ducts 30—31, which are communicatively connected to pipes 16 and 17 respectively. By rotation of the lever 23, disk 19 may be rotated to selectively supply air separately to the ducts 28, 29, 30 and 31, for controlling the delivery of air through pipes 14 and 15, to the clean-out ducts of the sand traps and pipes 16 and 17, to control the flow of air to the nozzles of sand traps for discharging sand onto the rails.

An auxiliary valve, generally designated 33, is mounted in the inlet casing-section 11, and controls the flow of air from a chamber 34, which is communicatively connected to the air supply pipe 13, through an opening 35, into the chamber 18. Valve 33 comprises a stem 36, which is slidably mounted in a cap 37, a packing 38 secured on a head 39 by a screw 40, and a washer 41. A spring 42 is adapted to normally close

the exposed face of the packing disk 38, against a seat, which surrounds the opening 35. The auxiliary valve is controlled by an arcuate cam 46, which is integral with and projects from, one face of the valve-disk 19, and an arm or lever 43, which is fulcrumed at 44 on the center of disk 19, has a V-shaped corner 45, engaged by cam 46 and an extension or abutment 47, which is adapted to engage a part of valve 33, such as the screw 40, to force valve 33 away from its seat, against the force of spring 42. Lever 23 is confined against rotation with disk 19, in a recess 56 in casing-section 11. Lever 43 is urged toward disk 19 by a spring 48, which is confined in a socket in casing-section 11, and exerts pressure against lever 43 for holding disk 19 against its seat 20. Cam 46 comprises V-shaped members 49, which are adapted to shift valve 33 to its open position when the disk 19 is rotated in opposite directions, to bring port 27 into registry with ducts 28, 29 respectively, for delivering air for the clean-out blasts, and raised end-portions 50, which are adapted to shift lever 43, to open valve 33, when the disk 19 is rotated to bring port 27 into registry with the ducts 30, 31 respectively, for the delivery of sand from the sand traps. V-shaped depressions 51 in cam 46, are provided to permit valve 33 to close between the clean-out blasts and the discharge of the sand from the sand traps. When disk 19 is in position to cut off flow of air through port 27, lever 43 engages a central V-shaped depression between members 49, and valve 33 will be closed. When valve 33 is in its open position, the pressure of spring 42, urges said valve toward its seat, and will also cause the V-shaped corner 45 of lever 43, to exert pressure on the inclined members of the V-shaped depressions in cam 46 for rotating the valve-disk into its cut-off positions.

The operation of the valve will be as follows: While lever 23 is in its neutral or central position, port 27 will be out of communication with any one of the ducts 28, 29, 30 and 31, which lead to the pipes 14, 15, 16, 17, respectively. Valve 38 will then be closed against its seat 40, and spring 42 will hold lever 43 against disk 19, and the flow of compressed air to chamber 18 will be cut off. The pressure of spring 42 applied to lever 43, will be transmitted to disk 19, to hold it in engagement with the seat 20. As a result, at all times while disk 19 is in its neutral position, valve 33 will be closed, and no compressed air can leak around valve-disk 20. When lever 23 is shifted to rotate disk 19, and bring port 27 into registry with conduit 28 or 29, for delivering clean-out blasts to the traps, cam members 49 will shift lever 43 so its extension 47 will shift valve 33 against the force of spring 42, and cause air to pass from pipe 13 via chamber 34 and opening 35, into chamber 18, and through port 27, to the selected conduit 28 or 29. When lever 23 is shifted and disk 19 is rotated to bring port 27 into registry with either of the conduits 30 or 31, one of the cam members 50 will shift lever 43 against the force of spring 48, and hold valve 33 open, while lever 23 remains set for discharging sand from the traps. When lever 23 is returned to its central position, from any of the positions in which it may have been set, disk 19 will be rotated to bring its port 27 out of registry with the conduits in the casing-section 10, and lever 43 will be retracted by spring 42, to release the auxiliary valve 33, and automatically cut off communication between the air supply pipe 13 and the chamber 18. When the lever 23 is inadvertently

left between its predetermined settings, according to the notches 26 in segment 25, for clean out blasts or discharging sand from the traps, respectively, the spring-pressure against lever 43 and the V-shaped corner 45 of said lever acting on the V-shaped depressions 51 in cam 46, will exert a rotative force on disk 19 to move it into the correct position for registry of its port 27 with one of the outlet conduits in the casing.

The invention exemplifies a controlling mechanism for a sand trap which comprises a rotatable valve-disk with a port therein, for controlling the delivery of sand to the sand traps, and an automatically closing auxiliary valve controlled by the disk, for cutting off the supply of air from the supply pipe to the disk chamber, so that there will be no leakage of air from the casing around the valve-disk when the sanding mechanism is not in operation. The invention also exemplifies an auxiliary valve which relieves the valve-disk of unilateral air-pressure, for reducing drag on the valve-disk and easing its operation.

The invention is not to be understood as limited to the details described, since these may be modified within the scope of the appended claims without departing from the spirit or scope of the invention.

Having thus described the invention, what we claim as new and desire to secure by Letters Patent is:

1. In controlling mechanism for a sand-trap provided with an air nozzle for discharging sand from the trap for application to a rail and a duct for a clean-out blast of the sand, the combination of a casing, means for supplying compressed air to the casing, the casing being provided with a seat and ports for air to the nozzle and to the clean-out duct in the trap, a rotatable disk having a face engaging said seat and provided with a port for selectively controlling air to said ducts, an auxiliary valve in the casing for cutting off the supply of air from the supply means to the disk, and cam means on and projecting transversely from the other face of the disk, including members for successively opening and closing the auxiliary valve during rotation of the disk to successively control air to the nozzle and the clean-out duct in the trap.

2. In controlling mechanism for a sand-trap provided with an air nozzle for discharging sand from the trap for application to a rail and a duct for a clean-out blast of the sand, the combination of a casing, means for supplying compressed air in the casing, the casing being provided with a seat and ports for air to the nozzle and to the clean-out duct in the trap, a rotatable disk having a face engaging said seat and provided with a port for selectively controlling air to said ducts, an auxiliary valve in the casing for cutting off the supply of air from the supply means to the disk, cam means integral with and projecting transversely from the other face of the disk, and including members for successively opening and closing the auxiliary valve during rotation of the disk to successively control air to the nozzle and the clean-out duct in the trap, and a lever shiftable by said members transversely to the disk.

3. In controlling mechanism for a sand-trap provided with an air nozzle for discharging sand from the trap for application to a rail and a duct for a clean-out blast of the sand, the combination of a casing, means for supplying compressed air to the casing, a rotatable valve disk in the casing, said disk and casing being provided with means for selectively controlling air to the nozzle

and the clean-out duct, an auxiliary valve in the casing for cutting off the supply of air from the supply means to the disk, cam means on and rotatable with the disk, and a lever movably supported in the casing for movement transversely of the disk by said cam means, for opening the auxiliary valve to deliver air to the disk when it is rotated to deliver air to the nozzle or to the clean-out duct in the trap.

4. In controlling mechanism for a sand-trap, provided with an air nozzle for discharging sand from the trap for application to a rail and a duct for a clean-out blast of the sand, the combination of a casing, means for supplying compressed air to the casing, a rotatable valve disk in the casing, said disk and casing being provided with means for selectively controlling air to the nozzle and the clean-out duct, an auxiliary valve in the casing for cutting off the supply of air from the supply means to the disk, cam means on and rotatable with the disk, and a lever movably mounted in the casing for movement transversely of and fulcrumed on said disk, for opening the auxiliary valve to deliver air to the disk when it is rotated to deliver air to the nozzle or the clean-out duct in the trap, and spring means for urging the lever in engagement with the cam means.

5. In controlling mechanism for a sand-trap provided with an air nozzle for discharging sand from the trap for application to a rail and a duct for a clean-out blast of the sand, the combination

of a casing, means for supplying compressed air to the casing, a rotatable valve disk in the casing, said disk and casing being provided with means for selectively controlling air to the nozzle and the clean-out duct, an auxiliary valve in the casing for cutting off the supply of air from the supply means to the disk, cam means on and rotatable with the disk, the casing being provided with a groove, and a lever confined in the groove for movement transversely of the disk and shiftable by said cam means for delivering air to the disk when it is rotated to deliver air to the nozzle or the clean-out duct in the trap, and a spring for urging the lever against the disk and into engagement with the cam means.
